(57) **CLAIM**

The ornamental design for a feed port for bird feeder, as shown and described.

DESCRIPTION

FIG. 1 is a perspective view of a feed port for bird feeder of the invention, in which the broken lines are for illustrative purposes only and form no part of the claimed design;

FIG. 2 is a perspective view of the feed port for bird feeder of FIG. 1;

FIG. 3 is a front view of the feed port for bird feeder of FIG. 1;

FIG. 4 is a rear view of the feed port for bird feeder of FIG. 1;

FIG. 5 is a right side view of the feed port for bird feeder of FIG. 1, the left side view being a mirror image thereof;

FIG. 6 is a top view of the feed port for bird feeder of FIG. 1; and,

FIG. 7 is a bottom view of the feed port for bird feeder of FIG. 1.
